UNITED STATES PATENT OFFICE

RALPH A. GROSS, OF LITITZ, PENNSYLVANIA, ASSIGNOR TO SIMPLEX PAPER BOX COMPANY, OF LITITZ, PENNSYLVANIA, A CORPORATION OF PENNSYLVANIA

COLLAPSIBLE PAPER BOX

Application filed January 11, 1929. Serial No. 331,841.

My invention consists in the novel features hereinafter described, reference being had to the accompanying drawings which show one embodiment of my invention selected by 5 me for purposes of illustration, and the said invention is fully disclosed in the following description and claims.

My invention consists in a novel knock-down or collapsible box capable of being 10 shipped flat and of being instantly erected and locked in operative position for use when desired, one member of the said box being provided with portions which when in the erected position of the box form cover rests 15 and at the same time assist in efficiently locking the box member of which they form a part in the erected position and impart additional rigidity to the box.

In the accompanying drawings, 20 Fig. 1 represents a longitudinal sectional view of complete box in operative position and arranged to hold cakes of soap indicated in dotted lines.

Fig. 2 is a perspective view showing the 25 two box members in separated relation.

Fig. 3 is a plan view of the blank for the bottom member of the box.

Fig. 4 is a plan view of the bottom member in knock-down condition for shipment.

30 Fig. 5 is a perspective view of a portion of the bottom member about to be erected into operative position.

Fig. 6 is a plan view of the blank for the top or cover member of the box.

35 Fig. 7 is a plan view of the top member in knock-down condition.

Fig. 8 is a partial perspective view similar to Fig. 5 of the top member in partly erected position.

40 Fig. 9 is a similar partial perspective view showing the top member fully erected and locked.

Fig. 10 is a section in line 10—10 of Fig. 9.

The embodiment of my invention herein 45 shown consists of a shallow bottom member indicated as a whole by the letter B, intended to hold articles (as cakes of soap for example) which project above the edges of said member, and a top or cover member indicated as a whole by the letter C, of greater

depth than the bottom member and adapted to telescope over the bottom member, and provided interiorly with what are termed "cover rests" for engaging the upper edges of the bottom member and limit the extent 55 to which the bottom member shall extend into the cover member. So far as I am aware this type of box has never before been made as a knock-down or collapsible box capable 60 of being shipped flat.

The bottom member B, is formed from a blank (see Fig. 3) of paper, cardboard or other sheet stock of the desired thickness, and is cut and scored or creased to facilitate 65 folding. The blank comprises the bottom, 1, main or exterior side flaps, 2, separated from the bottom by scores, 2^a, interior side flaps, 3, separated from the exterior side flaps by scores, 3^a, and having at their outer 70 edges the side locking flaps, 12, separated from the exterior side flaps by scores, 12^a, and provided at each end with a beveled portion, 13. The bottom 1, is also provided at 75 at opposite ends with exterior end flaps, 4, separated from the bottom by scores, 4^a, interior end flaps, 5, separated from the exterior end flaps by scores, 5^a, and end locking flaps, 15, separated from the interior end flaps by the scores, 15^a, and provided at opposite 80 ends with beveled portions, 16. At each corner of the bottom, 1, of the blank there are folding corner sections integrally 85 connected with the adjacent exterior end and side sections and divided by short slits, 6, and diagonal scores, 6^a, from the inner ends of the slits to the corners of the bottom, 1, into two sections, 7 and 8, which fold upon themselves and are folded upon the adjacent end folding sections, in erecting the box, (as shown in Fig. 5). Obviously these corner 90 sections could be folded upon the adjacent side sections if desired, but I prefer to fold them upon the end sections as shown, and it will be noted that the portions, 7, present elongated top portions, indicated at 9, which 95 extend inwardly along the inner face of the exterior end flaps as clearly shown in Fig. 5, so that when the interior end flap is folded over them they carry their reinforcing effect 100 inwardly a considerable distance from the

box corners and stiffen the end of the box. The slit, 6, I have found also facilitates folding these corner sections without buckling, as the fold on score, 6^a, does not have to go out to a point or corner as would otherwise be the case. The interior side flaps, 3, 3, are provided at each end with cutaway portions, 3^x, 3^x, and the ends of the interior end flaps, 5, are notched as at 5^x, 5^x, so that the portions beyond the notches will engage and interlock with the edges of the cutaway portions, 3^x, 3^x, of the interior side flaps as shown in Fig. 2.

The blanks for the bottom member could obviously be shipped flat, but I prefer to fold the interior side flaps, 3, on the exterior side flaps, 2, and the side locking flaps, 12, on the bottom and to secure them preferably adhesively, and I have shown the flaps, 3 and 12, gummed for this purpose in Fig. 3. I also prefer to gum the portions, 7, of the corner folds or otherwise secure them to the inner faces of the exterior end flaps, as shown in Fig. 4, thus making a compact box member which can be made up so far and shipped flat, and which can be instantly erected and locked by simply turning up the end flaps as shown in Fig. 5, which by reason of the scores, 6^a, in the corner pieces erects the side flaps, and then folding the interior end flaps, 5, down over the infolded corner flaps and the exterior end flaps, and bringing the end locking flaps into engagement with the bottom, 1, when the beveled ends, 16, will engage the beveled ends, 13, of the side locking flaps and securely lock the box in erected position, as shown in Fig. 2.

The blank for the top or cover member, C, is shown in Fig. 6 and the parts corresponding with those of the blank for the bottom member are given the same reference numerals with the addition of 100. The blank comprises the top, 101, side flaps, 102, 103, and side locking flaps, 112, the exterior end flaps, 104, and interior end flaps, 105, constructed and operating as previously described except that the exterior end flaps are not notched and the side and end flaps are of greater width than those of the bottom box member.

At the outer edge of the interior end flaps, 105, and separated therefrom by the score, 110^a, are a pair of rest-forming flaps, 110 and 111, separated from each other by the score, 111^a, and being of slightly greater length transversely of the box than the end flaps to provide locking projections, indicated at 110^b. At the outer edge of each rest flap, 111, and separated therefrom by the score, 112^a, is the end locking flap, 112, having the beveled ends, 113.

Fig. 7 shows the cover member partly made up, in the same manner as the bottom member, ready for shipment flat. In erecting the cover member C, the end flaps, 104, are raised to a vertical position (see Fig. 8) thereby bringing the side flaps into vertical position

as previously described with reference to Fig. 5. The rest flaps, 110 and 111, are then folded upon each other and are carried down into the cover member together with the locking flaps, 112, by folding the interior end flaps downwardly upon the inturned folded corner flaps. This brings the rest flaps into position against the inner face of the interior end flaps, and interlocks their projecting ends, 110^b, with the cutaway portions, 103^x, of the interior side flaps as clearly shown in Fig. 9, and the end locking flaps, 112, are brought into engagement with the top, 101, with their beveled ends, 116, engaging the beveled ends, 113, of the side locking flaps, 112. This holds the rest flaps, 110, 111, in position to form a stop to engage the upper edges of the bottom member as shown in Fig. 1, and the rest flaps will be of such width that when folded they will engage the box member just as the latter has telescoped the desired distance within the cover member, so that the bottom member cannot be pushed further in.

It will also be seen that the rest folds constitute a double thickness extending transversely of the box at each end and having the end portions thereof interlocked with the cutaway portions of the inner side flaps, 103, thus forming a locking brace extending entirely across the box at each end, which not only serves as the cover rest but tends to greatly strengthen the cover and add to its rigidity, while at the same time the natural tendency of two rest flaps to separate adjacent to the top, 101, of the top or cover member acts to press the inner end flaps, 105, firmly against the infolded corner portions and also to press the end locking flaps, 115, inwardly and hold their beveled ends, 116, firmly in engagement with the correspondingly beveled ends, 113, of the side locking flaps, thus assisting in the locking of the parts of the cover member in erected position. This is clearly shown in Fig. 10.

As previously stated Fig. 1 shows the two members of the box in closed or assembled relation, and Fig. 2 shows the same box in perspective in separated relation. It will thus be seen that this box which may be termed a "cover rest box" with the understanding that this term implies a box comprising two members, one of which is shallower than the other, the deeper member serving as the cover and being provided with a cover rest to engage the upper edges of the shallower member, may be formed from an integral blank so that the box may be shipped and stored in flat condition, preferably partly folded as indicated in Figs. 4 and 7, and the parts may be instantly erected into operative position and locked, when desired for use, while the integral cover rest portion performs an additional function in assisting in locking the parts of the cover member in erected position and forming a transverse

brace which stiffens the structure of the cover member. In addition to providing for the first time, so far as I am aware, a knockdown cover rest box, the provision of the extra rest flaps has integral parts of the blank adjacent to opposite edges of the central portion thereof, effects a material saving in the construction of this type of box member, as it avoids the labor of cutting out and pasting or otherwise securing extra pieces in the cover member to form the cover rests in addition to contributing to the locking, as well as the rigidity of the structure of the cover member.

What I claim and desire to secure by Letters Patent is:—

1. As a new article of manufacture, a knock-down box of the cover rest type comprising a cover member formed from an integral blank having a main top portion and folding side and end flaps constructed to interlock when in erected position, the blank at opposite sides being provided with extra folds connected with the outer edges of the adjacent flaps, said folds being of less width than the side and end folds and constructed to fold upon themselves and the connected flap, within the cover member, and form cover rests.

2. As a new article of manufacture, a knock-down box of the cover rest type comprising a cover member formed from an integral blank having a main top portion and folding side, and end flaps constructed to interlock when in erected position, portions of the blank at opposite sides of the main top portion being provided with extra folds of less width than the side and end folds constructed to fold upon themselves and form cover rests, the flaps on the other sides of the main portion having infolded portions constructed to engage the ends of the rest flaps when in the erected position.

3. As a new article of manufacture, a knock-down box of the cover rest type comprising a cover member formed from an integral blank having a main top portion and folding side, and end flaps constructed to interlock when in erected position, portions of the blank at opposite sides of the main top portion being provided with extra folds of less width than the side and end folds constructed to fold upon themselves and form cover rests, the flaps on the other sides of the main portion having infolded portions terminating in locking flaps to engage the main portion of the blank, and having the ends of said infolded portions constructed to engage the ends of the rest flaps, and said rest flaps being provided with a terminal locking flap for engaging the main body of the blank and interlock with the first mentioned locking flap.

4. As a new article of manufacture, a knock-down box of the cover rest type formed from an integral blank provided with a cen-

tral top portion having at its opposite sides exterior and interior side flaps constructed to fold upon each other, and at its opposite ends exterior and interior end flaps constructed to fold upon each other, infolding corner portions connecting the exterior side and end flaps and adapted to be enclosed between the interior and exterior end flaps and cover rest flaps formed integrally with the interior end flaps and adapted to fold upon the same, with in the box, said cover rest flaps having their end portions constructed to engage with the end portions of the interior side flaps when the cover member is in erected position, and hold the interior end flaps in engagement with said corner portions.

5. As a new article of manufacture, a knock-down box of the cover rest type formed from an integral blank provided with a central top portion, having at its opposite sides exterior and interior side flaps constructed to fold upon each other, and at its opposite ends exterior and interior end flaps constructed to fold upon each other, infolding corner portions connecting the exterior side and end flaps, and a pair of cover rest flaps formed integrally with each interior end flap and of less width than the latter, and adapted to fold upon themselves and upon the adjacent connected interior end flaps, and having their ends constructed to engage the end portions of the interior side flaps.

6. As a new article of manufacture, a knock-down box of the cover rest type formed from an integral blank provided with a central top portion, having at its opposite sides exterior and interior side flaps constructed to fold upon each other, and at its opposite ends exterior and interior end flaps constructed to fold upon each other, infolding corner portions connecting the exterior side and end flaps, and a pair of cover rest flaps formed integrally with each interior end flap and of less width than the latter, and adapted to fold upon themselves and upon the adjacent connected interior end flaps, and having their ends constructed to engage the end portions of the interior side flaps, the end portions of said interior side flaps being cutaway to accommodate the extra thickness of said cover rest flaps.

7. As a new article of manufacture, a knock-down box of the cover rest type formed from an integral blank provided with a central top portion, having at its opposite sides exterior and interior side flaps constructed to fold upon each other, and at its opposite ends exterior and interior end flaps constructed to fold upon each other, infolding corner portions connecting the exterior side and end flaps, and a pair of cover rest flaps formed integrally with each interior end flap and of less width than the latter and adapted to fold upon themselves and upon

the adjacent connected interior end flaps, and having their ends constructed to engage the end portions of the interior side flaps, the end portions of said interior side flaps being 5 cutaway to accommodate the extra thickness of said cover rest flaps, the interior side flaps and the innermost rest flap being provided with locking flaps for engaging the central portion, said locking flaps having 10 beveled portions brought into interlocking engagement when the cover member is erected.

8. As a new article of manufacture, a knock-down box of the cover rest type 15 formed from an integral blank provided with a central top portion, having at its opposite side exterior and interior side flaps constructed to fold upon each other, and at its opposite ends exterior and interior end flaps 20 constructed to fold upon each other, infolding corner portions connecting the exterior side and end flaps, and a pair of cover rest flaps formed integrally with each interior end flap and of less width than the latter, 25 and adapted to fold upon themselves and upon the adjacent connected interior end flaps, and having their ends constructed to engage the end portions of the interior side flaps, the end portions of said interior side 30 flaps being cutaway to accommodate the extra thickness of said cover rest flaps, said infolded corner portions having parts folded upon and connected with the adjacent exterior end flaps and serving to automatically 35 raise the side flaps into erected position when the exterior end flaps are raised into erected position, the interior end flaps and said rest flaps folding against said infolded corner portions when the cover member is in 40 erected position.

9. As a new article of manufacture, a knock-down box of the cover rest type 45 formed from an integral blank provided with a central top portion, having at its opposite sides exterior and interior side flaps constructed to fold upon each other, and at its opposite ends exterior and interior end flaps constructed to fold upon each other, infolding corner portions connecting the exterior side and end flaps, and a pair of cover 50 rest flaps formed integrally with each interior end flap and of less width than the latter, and adapted to fold upon themselves and upon the adjacent connected interior end flaps, and having their ends constructed to engage the end portions of the interior side flaps, the end portions of said interior side flaps being cutaway to accommodate the extra thickness of said cover rest flaps, said infolded corner portions having parts folded upon and connected with the adjacent exterior end flaps and serving to automatically 55 raise the side flaps into erected position when the exterior end flaps are raised into erected 60 position, the interior end flaps and said rest flaps folding against said infolded corner portions when the cover member is in erected position.

flaps folding against said infolded corner portions when the cover member is in erected position, the interior side flaps and the inner 70 of said raised flaps being provided with locking flaps for engaging the said central portion, said locking flaps having beveled end portions constructed to be brought into locking engagement.

In testimony whereof I affix my signature.

RALPH A. GROSS.
